No. 802,533.

PATENTED OCT. 24, 1905.

E. S. STIMPSON.

MEANS FOR LOADING HOPPERS OF FILLING REPLENISHING LOOMS.

APPLICATION FILED JULY 7, 1905.

UNITED STATES PATENT OFFICE.

EDWARD S. STIMPSON, OF HOPEDALE, MASSACHUSETTS, ASSIGNOR TO DRAPER COMPANY, OF HOPEDALE, MASSACHUSETTS, A CORPORATION OF MAINE.

MEANS FOR LOADING HOPPERS OF FILLING-REPLENISHING LOOMS.

No. 802,533.

Specification of Letters Patent.

Patented Oct. 24, 1905.

Application filed July 7, 1905. Serial No. 268,642.

To all whom it may concern:

Be it known that I, EDWARD S. STIMPSON, a citizen of the United States, and a resident of Hopedale, county of Worcester, State of Massachusetts, have invented an Improvement in Means for Loading Hoppers of Filling-Replenishing Looms, of which the following description, in connection with the accompanying drawings, is a specification, like characters on the drawings representing like parts.

This invention has for its object the production of means for facilitating the loading of the filling-feeders or hoppers of automatic looms of the Northrop type, such as are shown in the United States patent to Northrop, No. 529,940, and other patents of later date. In such looms the hopper comprises two connected and rotatable disks, one of which is provided with a series of peripheral pockets open at their outer ends to receive the butts of the filling-carriers or bobbins, the other disk carrying an oppositely-located series of tip-holders controlled by springs to yieldingly engage the tips of the filling-carriers, which are thus held in a circularly-arranged series. Means are provided to rotate the hopper intermittently to bring the filling-carriers one by one into position to be transferred to the shuttle, all in a well-known manner. A fixed flange on the hopper-stand overhangs the open ends of the pockets and serves to prevent any accidental removal of the filling-carriers before the proper time. The attendant loads the hopper by inserting the filling-carriers one by one, first inserting the butt in a pocket within the flange and then pushes down the tip into engagement with the tip-holder opposite until a sufficient load is held by the hopper.

My present invention has for its object the production of means for facilitating the loading operation, whereby a gang or several filling-carriers may be simultaneously inserted in the hopper as easily and quickly as one can now be inserted. This I accomplish by means of a loading device which temporarily sustains a plurality of filling-carriers in such position that they can be very slight manipulation be readily inserted simultaneously in the hopper, after which the loading device is withdrawn by an endwise movement, my invention requiring no change or alteration in the con-

struction or arrangement of the hopper or in the construction of the filling-carriers themselves.

55

The various novel features of my invention will be fully described in the subjoined specification, and particularly pointed out in the following claims.

Figure 1 is a top plan view of a sufficient portion of a hopper of the type described to be understood, showing a plurality or gang of filling-carriers being placed therein by means of a loading device embodying my invention. Fig. 2 is a vertical section on the irregular line 2 2, Fig. 1, showing the filling-carrier and the handle of the loading device in elevation. Fig. 3 is a view in elevation of the loading device. Fig. 4 shows a face view and longitudinal section of one of the tip-holders detached and enlarged with which the hopper is provided, and Fig. 5 is a detail of the loading device as it would appear if viewed from the left, Figs. 1 and 2.

Referring to Fig. 1, the hopper-stand A⁷, mounted on the breast-beam A¹⁰ of the loom, the connected disks a a', Fig. 2, the former having a series of open-ended pockets, as 2, around its periphery for the butts m^x of the filling-carriers m, the flange c on the stand and overhanging the open ends of the pockets 2 throughout the greater part of the periphery of disk a, may be and are of well-known construction in Northrop looms. I have herein shown the disk a' as provided with tip-holders h^x, mounted to rock on the lip or flange a¹⁴ on the disk and pressed inward by springs, as s^x, Fig. 2, substantially as in the United States patent to Stimpson, No. 755,252, dated March 22, 1904, as the tip-holder therein shown is readily operative in connection with the loading device to be described. The socket or seat h⁴ in the upper end or head of each tip-holder receives the tip m' of the filling-carrier or bobbin when the butt m^x thereof is inserted in the opposite pocket, as will be understood by those familiar with such apparatus, and the head of each tip-holder is notched, as at h¹⁰, for the filling end to lead through to the disk or end-holding plate b². (See dotted lines, Fig. 1.) I have not shown any of the tip-holders in Fig. 1, inasmuch as they would confuse the drawing.

In accordance with present practice the operative takes up a bobbin, inserts the butt beneath the flange c into an empty pocket, and then pushes the tip down into operative engagement with the opposite tip-holder, after which the filling end is carried over to the end-holding disk b^2 and secured. By means of my present invention I am enabled to insert simultaneously a group or gang of filling-carriers into the hopper as rapidly as one is now inserted. To this end I provide a curved base-piece 3, Fig. 5, having a handle 4 rigidly secured to it and projecting from one side thereof, the base-piece corresponding in curvature to the curvature of the hopper-disk a' . On the side of the base-piece opposite the handle are a series of pins or supports 5, herein shown as five in number, equidistant from each other and in parallelism and of such diameter that they will loosely enter the tip ends of and support a like number of filling-carriers with their butts outward.

In Fig. 1 the group of filling-carriers are shown on the loading device just after the butts have been inserted in the pockets of the butt-holding disk a , and the right hand of the operative is shown in dotted lines grasping the handle, while the left hand presses down the group or gang of bobbins into engagement with the tip-holders h^x .

As shown in Figs. 2 and 3, the inner end of each support 5 is bent upward, as at 6, and then into parallelism with the main portion 35 of the support under the overhanging flange 7, which forms a part of and strengthens the base-piece 3. This upward bend to the inner ends of the supports serves to clear the portions of the hopper-disk between the tip-holders h^x , and it also serves to form a stop for the tip end of the bobbin on each support, positioning them with their butts substantially in the same plane, so that all can be inserted in a corresponding number of pockets, 45 By clearing the periphery of the disk the body portions of the supports can be depressed sufficiently to bring the bobbin-tips into engagement with the recessed inner faces of the tip-holders, as in Fig. 2, and as 50 the operator with the right hand draws the loading device to the right, Figs. 1 and 2, with an endwise movement the left hand presses or snaps the several tips into the seats h^x and the loading is completed. The filling 55 ends are then carried over disk b^2 and fastened.

Of course the full quota of bobbins need not be used; but I have found that five is a convenient number to handle and insert as a group into the hopper.

60 In preparing the loading device it is held in the right hand with the supports 5 upturned, and the bobbins are slipped on tips down, a matter of a few seconds, after which they are loaded into the hopper.

65 My invention requires no change in the

hopper, and hence can be used with the hoppers of looms now in use and of the type hereinbefore referred to.

Having fully described my invention, what I claim as new, and desire to secure by Letters Patent, is—

1. In a loom, a rotatable hopper comprising two connected disks, one having a circularly-arranged series of butt-receiving pockets and the other having oppositely-located tip-holders, for the filling-carriers, a fixed flange overhanging the outer ends of the pockets, and a removable gang-loader comprising a series of parallel, rigidly-connected supports each adapted to loosely sustain a filling-carrier butt outward, and an attached handle, whereby the butt-ends of a plurality of filling-carriers can be simultaneously inserted beneath the flange in the pockets of the hopper and their tip ends depressed into engagement with the tip-holders, withdrawal of the loading device longitudinally of the filling-carriers leaving the same in the hopper. 75 80 85

2. In a loom, a rotatable hopper having butt-receiving pockets and opposite tip-holders, for the butts and tips respectively of a circularly-arranged series of filling-carriers, and a removable loading device comprising a base-piece curved to correspond to the series of holding means on the hopper, a series of parallel supports rigidly mounted on said base-piece and each adapted to loosely sustain a filling-carrier butt outward, and an oppositely-extended handle on the base-piece, whereby the butts of a plurality of filling-carriers may be seated in the pockets and their tips depressed into engagement with the opposite tip-holders before withdrawal of the loading device. 90 95 100

3. In a loom, a rotatable hopper having butt-receiving pockets and opposite tip-holders, for the butts and tips respectively of a circularly-arranged series of filling-carriers, and a removable loading device having means to loosely sustain a plurality of filling-carriers butts outward in position to be seated in the pockets and thereafter have their tips depressed into engagement with the tip-holders. 105 110 115

4. In a loom, a rotatable hopper having butt-receiving pockets and opposite tip-holders, for the butts and tips respectively of a circularly-arranged series of filling-carriers, and a removable loading device having means to loosely sustain a plurality of filling-carriers butts outward side by side in position 120 to have their butts simultaneously seated in a corresponding number of pockets and their tips depressed into the tip-holders opposite thereto.

5. A loading device for inserting a plurality of filling-carriers into the butt and tip holding devices of the rotatable hopper of a loom, comprising a curved base-piece having an attached handle, and on the opposite side of the base-piece a series of parallel supports 125 130

adapted to loosely enter the tip ends of the filling-carriers, to temporarily support the same when they are simultaneously seated in a corresponding number of butt and tip holding devices of the hopper.

6. A loading device for inserting a plurality of filling-carriers into the butt and tip holding devices of the rotatable hopper of a loom, comprising a curved base-piece having an attached handle, projecting from one side, and on the opposite side a series of rigidly-attached, parallel supports to loosely enter the tip ends of the filling-carriers, to tempo-

rarily support the same for simultaneous insertion in the butt and tip holding devices of the hopper, each support being bent at its inner end to clear the tip-holding devices and to form stops for the tips of the filling-carriers.

In testimony whereof I have signed my name to this specification in the presence of two subscribing witnesses.

EDWARD S. STIMPSON.
